CASSETTE TRANSPORT

Hari Matsuda, Evanston, Ill., assignor to Ampex Corporation, Redwood City, Calif., a corporation of California

Filed Nov. 3, 1969, Ser. No. 19,898

Term of patent 14 years

Int. Cl. D14—01

U.S. Cl. D26—14

The figure is a front, top and left side perspective view of a cassette transport, showing my new design.

The rear side being conventionally plain, and the right side of the transport and the forward face of the top recess being mirror images of the left side of the transport and the rearward face of the top recess, respectively.

I claim:

The ornamental design for a cassette transport, substantially as shown and described.
